CLAIM

The ornamental design for a knife handle, as shown and described.

DESCRIPTION

FIG. 1 is a front elevation view of a knife handle showing my new design;

FIG. 2 is a top plan view showing the knife handle of FIG. 1;

FIG. 3 is a bottom plan view showing the knife handle of FIG. 1;

FIG. 4 is a right side elevational view showing the knife handle of FIG. 1;

FIG. 5 is a left side elevational view showing the knife handle of FIG. 1;

FIG. 6 is a cross-sectional view taken along line 6—6 of FIG. 1;

FIG. 7 is a cross-sectional view taken along line 7—7 of FIG. 1;

FIG. 8 is a cross-sectional view taken along line 8—8 of FIG. 1;

FIG. 9 is a cross-sectional view taken along line 9—9 of FIG. 1; and,

FIG. 10 is a perspective view showing the knife handle of FIG. 1.

The broken lines shown in FIGS. 1—5 and 10 are for illustrative purposes only and form no part of the claimed design.
